UNITED STATES PATENT OFFICE.

JULIUS RUND, OF FRANKFORT-ON-THE-MAIN, GERMANY.

BALLOON-ENVELOP MATERIAL.

1,001,892.

Specification of Letters Patent. Patented Aug. 29, 1911.

Application filed July 5, 1910. Serial No. 570,464.

To all whom it may concern:

Be it known that I, JULIUS RUND, subject of the Emperor of Germany, residing at Goethestrasse 10, Frankfort-on-the-Main, 5 Germany, have invented a certain new and useful Balloon-Envelop Material, of which the following is a specification.

This invention relates to material for the envelops of balloons and the like. The 10 properties which such material must possess are particularly great resistance to tearing and impermeability to gases, and other desirable features of the material are that it should protect the caoutchouc lining from 15 the influence of light and the contained gas from large temperature variations.

It is understood, of course, that the improvements in the material should not introduce any unnecessary increase in the 20 weight or cost of the same.

The object of the present invention is a material for balloon envelops, which will possess the above mentioned qualities, which change according as the balloon is to remain 25 inflated for a long period (as in the case of a motor balloon), or one which is inflated for a short period (say an aerostat).

The present invention consists substantially in an improved material for the envelops of balloons, having strong threads spaced at intervals in the weft and warp and weaved into or on to the material for the purpose of increasing its resistance to tearing. The tearing resistance of the material can also be increased by a binding of 30 net or gauze fabric of strong threads placed between smooth fabrics. In this case reinforced fabric in combination with smooth fabrics may be used.

40 For the prevention of diffusion of the inclosed gas, indiarubber has hitherto provided itself particularly useful in rendering the envelop impermeable. On account of its cost, only a thin coating of indiarubber can 45 be employed. According to the present invention of a layer of fibrous material such as paper, felt or the like is used as the gas tight material, and is united to the fabric by an adhesive, preferably chrome glue. A 50 particularly high degree of gas tightness can be obtained if in addition to the layer of glue and fibrous material a thin coating of indiarubber is provided, for example it may be laid on to the latter layer. In order

to prevent the decomposition of the indiarubber by the rays of light, the fibrous layer may consist of yellow paper in which case also yellow coloring matter may be added to the adhesive. 55

The outer surface of the material is kept 60 bright and acts so that the sun rays striking the material are for the greater part reflected away. In order however to provide great security against the penetration of heat through the material, according to the 65 present invention, it is provided on its inner surface with a layer of paper, felted wool, thin flannel, or the like. This layer also prevents too rapid cooling of the gases.

The drawing illustrates in Figures 1 and 70 2 two varieties of material for balloon envelops according to the present invention.

The envelop material according to Fig. 1, consists of an outside layer of fabric *a*, which is reinforced by strong threads *b* in 75 the weft and warp weaved into or on to the fabric; on this fabric a thin layer of paper *c* is attached with chrome glue or the like, this layer being provided with a thin coating *d* of indiarubber, and on this finally 80 is arranged a layer of felt or flannel *e*.

When very great demands in respect to the hereinbefore cited properties are required from the material, the combination illustrated in Fig. 2 is advisable. This consists of a reinforced fabric *a'* on the outside, if desired in combination with a smooth fabric *a''*, a layer of paper *c'* attached to the fabric with chrome glue, a layer of indiarubber *d'*, a layer of fabric *a''* with a second 90 layer of indiarubber *d''* and as inmost layer one of felted wool or other thin flannel like fabric *e'*.

Having now described my invention what I claim as new and desire to secure by Letters Patent is:—

1. Balloon envelop material consisting of a fabric one smooth side and reinforced by strong threads spaced at intervals in the weft and warp and woven with the material and projecting from the other side. 100

2. Balloon envelop material consisting of a layer of fabric reinforced by strong threads spaced at intervals in the weft and warp, and a layer of smooth fabric joined 105 to said first named layer.

3. Balloon envelop material consisting of a plurality of united layers of fabric each

- reinforced by strong threads spaced at intervals in the weft and warp and projecting from one side only of the fabric.
4. Balloon envelop material consisting of 5 fabric reinforced by strong threads spaced at intervals in the weft and warp, and a layer of fibrous gastight material united with said first named layer.
5. Balloon envelop material consisting of 10 smooth fabric and layer of paper attached thereto by an adhesive for gastightness.
6. Balloon envelop material consisting of 15 fabric reinforced by strong threads in the weft and warp and a layer of paper adhered thereto for gastightness.
7. Balloon envelop material consisting of 20 fabric reinforced by strong threads in the weft and warp, a layer of indiarubber and united therewith, and a layer of light proof material for preventing decomposition of the indiarubber and united therewith.
8. Balloon envelop material of fabric reinforced by strong threads in the weft and 25 warp, a layer of indiarubber united therewith, a layer of light proof material for preventing decomposition of the indiarubber united therewith, and a layer of non-conducting material as protection against temperature variations.
- 30 9. Balloon envelop material of fabric reinforced by strong threads in the weft and warp, a layer of fibrous gastight material, attached thereto, and a layer of non-conducting material as protection against temperature variations.
- 35 10. Balloon envelop material of fabrics reinforced by strong threads in the weft and warp, a gastight layer attached thereto of fibrous material, a layer of indiarubber, and a layer of non-conducting material.
11. Balloon envelop material of reinforced fabric, a layer of gastight fibrous material attached thereto, a layer of indiarubber, a layer of smooth fabric, and a layer of indiarubber attached to the latter.
12. Balloon envelop material of reinforced fabric, a layer of gastight fibrous material attached thereto, a layer of indiarubber, a layer of reinforced fabric and a layer of indiarubber attached to the latter.
13. Balloon envelop material of reinforced fabric, a thin gastight layer of paper attached thereto by suitable adhesive, a coating of indiarubber on the latter layer, and a non-conducting layer of thin flannel.
14. Balloon envelop material of reinforced fabric, a gastight fibrous layer attached thereto having a coating of indiarubber, a layer of reinforced fabric also having a coating of indiarubber, and an inmost layer of non-conducting material.
15. Balloon envelop material of smooth fabric, a gastight fibrous layer attached thereto having a coating of indiarubber, a layer of reinforced fabric also having a coating of indiarubber, and an inmost layer of non-conducting material.

In testimony whereof I have signed my name to this specification in the presence of two subscribing witnesses.

JULIUS RUND.
